TIMING MECHANISM.

1,134,391.

Specification of Letters Patent.

Patented Apr. 6, 1915.

Application filed March 14, 1912. Serial No. 633,898.

To all whom it may concern:

Be it known that I, FRANK M. LEAVITT, a citizen of the United States, residing in Smithtown, in the county of Suffolk and State of New York, have invented certain new and useful Improvements in Timing Mechanism, of which the following is a specification.

This invention relates to mechanism for performing any prescribed act at the end of a given period of time. The act may be the affecting of a controlled part, as for example the starting or stopping of such part. The timing mechanism responds to the movement of some operating part, such for example as a revolving shaft, the movement of which may be at a uniform or at a variable rate. The time between the starting point and the culmination of the operation is determined by (1) the rate of movement of the impelling part, that is in the case of a revolving shaft its speed of rotation; (2) the starting point which determines the distance to be traveled before the culmination, and the location of which point is adjustable; and (3) the gearing ratio or the extent to which the movement is reduced or slowed by an intermediate gear or gears.

Such timing apparatus are useful for many purposes in various types of machinery. An important field of usefulness is in the mechanism of automobile torpedoes. In such torpedoes timing mechanisms are or may be used (1) to control the starting of the engine upon launching to delay its full speeding until time has been afforded for the immersion of the torpedo; (2) to control the period during which the gyroscope is spun and determine the instant at which it shall be unlocked and set free; (3) to control the time of ignition of the fuel in the superheater; (4) to determine the duration of the run of the engine which is terminated by shutting off the air, accompanied commonly by the operation of means for causing the flotation of the torpedo if a practice run, or for causing the sinking of the torpedo during use in war in case it fails to strike its target and explode within the predetermined time.

In the accompanying drawings one form or embodiment of my invention is shown, the timing mechanism receiving its motion from a worm on a rapidly revolving shaft

and serving upon completing its run to withdraw a latch and thereby release a spring-pressed slide.

Figure 1 is a sectional elevation of the mechanism. Fig. 2 is a sectional elevation thereof on a plane perpendicular to that of Fig. 1. Fig. 3 is an enlarged section of the adjustable spring case. Fig. 4 is a sectional elevation, showing a modification of Fig. 3.

Referring to the drawings, A is the impeller or motor shaft by which the timing mechanism is driven, and B is the moving part, the time of operation of which it is the function of the timing mechanism to determine. This moving part B is shown as a slide which receives (through a lever C' or otherwise) the stress of a spring C impelling it in the direction of the arrow, and is held locked against this stress by a bolt or latch D until this latch is withdrawn by the operation of the timing mechanism. This latch is pressed by a spring D' into engagement with a notch or shoulder B' on the slide B, in order to lock the latter; and is unlocked or released by being encountered by a slide or other moving part E which I will call the "traveler", and which may have a greater or less movement before it encounters the latch.

The shaft A may be driven by any means whatever, as for example by a turbine A', and may serve any desired purpose in the construction of the torpedo or other apparatus to which the present invention may be applied. For example, it may carry a pinion A² for driving the fly wheel of the gyroscope in order to spin up the latter. The shaft A carries a worm *a* which meshes with a worm wheel *b* which constitutes one end of a gearing-down train F, which train may include a greater or lesser number of gears according to the duration of time to be introduced as a constant. In the particular construction shown the gear *b* has fixed upon its spindle a pinion *c* which meshes with a gear *d* upon the spindle 100 of which is fixed a pinion *e*, the latter constituting the terminus of the train, and being adapted to mesh with a rack *f* on the traveler E. The train F is carried by a frame G supported in any suitable manner, 105 being shown as carried by the slide B. The purpose of mounting this frame upon the slide is that when the slide is locked the

pinion *e* shall be in mesh with the rack *f*, but upon the unlocking of the slide and its displacement by its spring it shall carry the pinion *e* out of mesh with the rack *f*, as shown in Fig. 1.

For restoring the traveler *E* to its starting point and for enabling its starting point to be varied, it is connected to a spring-pressed part *H* shown in the form of a lever, 10 which part is so connected to a spring *S* that the stress of the latter serves to bring it back to a determined starting point whenever it is displaced therefrom. A simple construction is that shown in Fig. 3 wherein the spring 15 *S* is coiled around a rod *I* which is adapted to slide in a spring carrier or barrel *K* inclosing the spring. The spring bears at its opposite ends against loose washers or followers *J J'*, and these in turn bear against 20 normally coinciding shoulders on the rod *I* and in the barrel *K*. The shoulders on the rod *I* are lettered *i j* and those in the barrel *K* are lettered *g h* respectively. The shoulder *j* is formed by the end of a sleeve 25 *j'* which is suitably fastened on the rod *I*. The shoulder *h* is likewise formed in a part separable from the barrel *K*, being in the shape of a screw plug *h'*. These details, however, may be varied at will. In operation 30 any displacement of the rod *I* to either side of the normal position causes the shoulder on the rod at one end to engage the corresponding follower and forces it toward the middle, thereby compressing the spring between this follower and the other one which 35 remains seated against the shoulder in the barrel. The stress of the spring therefore tends to restore the parts to the normal central position. The parts are shown partly 40 displaced in Fig. 3. The effect of this construction is to restore the traveler *E* to its starting position after each operation immediately upon its being set free by the unmeshing of the pinion *e* and rack *f*.

45 For making the period of operation controllable at will, it is only necessary to provide means for adjusting the starting point of the traveler so that it shall have to travel a greater or lesser distance before reaching 50 its stopping point. To accomplish this I provide an adjustment whereby to displace the mounting of the double-acting spring. This is most conveniently accomplished by making the spring barrel *K* adjustable 55 longitudinally in a suitable support *K'*. The support *K'* is shown as a split bracket having a clamping screw *L* so that the barrel or spring carrier *K* might be given a sliding adjustment and be clamped in place 60 by this screw after such adjustment. It is preferable, however, to make the barrel rotative and screw-threaded upon its exterior as shown, and provide it with a knurled head *m* by which to turn it. It is thus readily 65 adjusted by first slackening off the screw *L*,

then turning the spring barrel until the traveler *E* is brought to the desired point, and then tightening the screw *L* to retain the adjustment. In Fig. 2 the center line *x* shows the center of the lever *H* at the starting position and the line *x'* shows another one of the various starting positions to which the device might be adjusted.

To set the apparatus for operation, it is only necessary to push the slide *B* into the position at which it is to be locked, whereupon the latch *D* enters its notch *B'* and locks it. The displacement of the slide carries the train frame *G* to such position as to bring the pinion *e* into mesh with the rack *f*. The parts are now ready for starting. Suppose now the shaft *A* is set in rotation as for example by admitting air to spin the turbine *A'*. Motion is communicated by the worm *a* to the train *F* which reduced by the train imparts a proportionately slower motion to the traveler *E*, which thereupon begins to move toward the latch *D*. The movement of the traveler is made against the stress of its spring *S*. The time required to complete its movement depends upon the length of its travel, which in turn depends upon the point from which it started as determined by the adjustment of the spring barrel *K* already described. At 90 the end of its movement it strikes the latch *D* and forces the latter back so that it unlocks the slide *B*, and this slide then is moved by its spring to the position in Fig. 1. This movement carries the pinion *e* out of mesh with the rack *f* and thereby sets free the traveler *E*, whereupon the spring *S* immediately restores the traveler to its starting point ready for the next operation.

The timing mechanism thus described may be greatly varied in mechanical details and in arrangement of parts according to the particular purpose for which it may be applied. The construction shown is a suitable example of its embodiment, and is the one best adapted to the particular purpose in view.

Instead of taking motion from an air driven shaft *A* the mechanism may be impelled by any moving part whatsoever, the movement of which is suitable for the purpose. It is not necessary that it be one moving at constant speed, although this may be desirable in some instances. With the turbine-driven shaft *A* for example the speed is variable, accelerating from zero to a very high rotation during the operation of the timing device.

The part controlled by the timing device, which in the construction shown is the slide *B*, may be any one of a great variety of parts, moving in a rectilinear, rotative, or other direction, and the movement of which may control any desired mechanism.

An example of one modification of which

this invention is susceptible is shown in Fig. 4. Here the coiled spring S is replaced by a spring S'. The barrel K is replaced by a slide K² and the intervening lever H is omitted so that the spring S' directly engages a recess in the slide or traveler, a fragment only of which is shown, being here lettered E'. The slide K² has a recess or opening p through which the ends of the spring pass and beyond which they project into the recess q in the traveler. The ends of these respective recesses take the place of the shoulders g h i j in Fig. 3. In the position shown the ends of the spring which tend to separate bear equally upon the ends of the respective recesses. If the traveler slide E' is displaced in either direction, it carries with it one end of the spring and leaves the other end bearing against the opposite shoulder of the recess p, so that the stress of the spring tends to restore the traveler to the central position shown. This central or starting position is adjustable by displacing the slide K² by means of an adjusting screw r. The operation is essentially the same as that of the construction first described.

What I claim is:—

1. A timing mechanism comprising an impelling part, a controlled part, a lock for the latter, a traveler driven from said impelling part and moving a determined distance to operate said lock to release said controlled part, and means operated at the end of the movement of the traveler for disconnecting it from the impelling part so that it is no longer driven thereby.

2. A timing mechanism comprising an impelling part, a controlled part, a lock for the latter, a traveler driven from said impelling part and moving a determined distance to operate said lock to release said controlled part, and means in connection with said controlled part for disconnecting the traveler from the impelling part to stop the driving of the traveler upon the release and displacement of the controlled part.

3. A timing mechanism comprising an impelling part, a controlled part, a lock for the latter, a traveler, a rack and pinion connection between the impelling part and traveler whereby the latter is driven, a traveler adapted to move a determined distance to operate said lock and release said controlled part, and means acting upon the movement of the controlled part to separate said rack and pinion to stop the driving of the traveler whereby the parts remain inoperable until

the return of the controlled part to its locked position.

4. A timing mechanism comprising an impelling part, a controlled part, a lock therefor, a timing traveler driven from said impelling part, and operating said lock to release said controlled part, means for freeing the traveler upon such operation, and retracting means for restoring the traveler to its starting point when so freed.

5. A timing mechanism comprising an impelling part, a reducing train driven therefrom, a controlled part, a lock therefor, a traveler driven from said train and operating said lock to release said controlled part, a connection between the controlled part and train whereby upon such release the train is unmeshed from the traveler to free the latter, and retracting means for restoring the traveler to its starting point.

6. In a timing mechanism, a movable traveler, adjustable restoring means therefor comprising a double-acting spring, an adjustable carrier therefor, and opposite coinciding stop shoulders on said carrier and on a part connected with said traveler respectively.

7. In a timing mechanism, a movable traveler, adjustable restoring means therefor comprising a coiled spring, a rod passing through said spring connected to the traveler, and an adjustable carrier for said spring, said rod and carrier having normally coinciding shoulders between which said spring is confined, whereby upon the displacement of said rod in either direction the spring is compressed and its stress tends to restore the rod and traveler to the starting position.

8. In a timing mechanism a controlled part, a lock therefor, said controlled part tending when released to move from its locked position, an impelling part, a reducing train driven therefrom, a bearing support for said train carried by said controlled part, a timing traveler having a rack driven from said train, said rack in mesh with a pinion of said train in the locked position of the controlled part, and said parts carried out of mesh by the movement of said controlled part when released.

In witness whereof, I have hereunto signed my name in the presence of two subscribing witnesses.
